FONT OF TYPE

Charles R. Lee, 7228 Spruce Ave.,
Takoma Park, Md. 20012

Filed Dec. 24, 1970, Ser. No. 26,634

Term of patent 14 years

Int. Cl. D18—03

U.S. Cl. D64—12

FIG. 1.

A B C D E F G H I J K
L M N O P Q R S T U V
W X Y Z 1 2 3 4 5 6 7 8 9
a b c d e f g h i j k l m n o p q r s t u v w x y z

FIG. 2.

L M N O P Q R S T U
V W X Y Z 1 2 3 4 5 6
7 8 9

FIG. 3.

SPRUCE

FIG. 4.

A B C D E F G H I J K L M N O P
Q R S T U V W X Y Z 1 2 3 4 5 6 7
8 9

FIG. 1 is a face view of a font of type showing my new design;

FIG. 2 is a face view of another embodiment of the font of type shown in FIG. 1 illustrating the expanded form of the upper case letters and numerals thereof;

FIG. 3 is a face view of another embodiment thereof illustrating for example the bold form of the upper case letters SPRUCE; and

FIG. 4 is a face view of still another embodiment of the font of type shown in FIG. 1 illustrating the condensed form of the upper case letters and numerals.

I claim:

The ornamental design for a font of type, substantially as shown and described.
